UNITED STATES PATENT OFFICE

130,207

DESIGN FOR A BADGE OR THE LIKE

Ramiro Monedero, San Salvador, El Salvador

Application August 15, 1941, Serial No. 102,849

Term of patent 3½ years

To all whom it may concern:

Be it known that I, Ramiro Monedero, a citizen of El Salvador, and a resident of San Salvador and Republic of El Salvador, Central America, have invented a new, original, and ornamental Design for a Badge or the like, of which the following is a specification, reference being had to the accompanying drawing, forming part thereof:

In the drawing, Figure 1 is a front elevational view of a badge showing my new design, and Figure 2 is a bottom plan thereof.

I claim:

The ornamental design for a badge or the like, as shown.

RAMIRO MONEDERO.
